UNITED STATES PATENT OFFICE.

WALTER F. WOLF, OF NEW YORK, N. Y.

DESIGN FOR A COMBINED BOOKHOLDER AND POCKETBOOK.

Application filed June 4, 1927. Serial No. 22,324. Term of patent 14 years.

To all whom it may concern:

Be it known, that I, WALTER F. WOLF, a citizen of the United States, residing at New York city, in the county of New York, and State of New York, have invented a new, original, and ornamental Design for a Combined Bookholder and Pocketbook, of which the following is a specification, reference being had to the accompanying drawing, forming part thereof.

In the drawings:—

Figure 1 is a perspective view looking from one side of the article.

Figure 2 is a similar view looking at the other side.

Figure 3 is an end elevation.

I claim:—

The ornamental design for a combined bookholder and pocketbook, as shown.

WALTER F. WOLF.
